UNITED STATES PATENT OFFICE.

FREDERICK L. SATTLEY, OF INDIANAPOLIS, INDIANA.

COIN-PACKAGER.

990,910.

Specification of Letters Patent.

Patented May 2, 1911.

Application filed November 9, 1909. Serial No. 527,056.

To all whom it may concern:

Be it known that I, FREDERICK L. SATTLEY, a citizen of the United States, residing at Indianapolis, in the county of Marion and 5 State of Indiana, have invented certain new and useful Improvements in Coin-Packagers, of which the following is a specification.

The object of my invention is to provide the hereinafter described improvements in 10 details of construction of a coin packaging mechanism of the general type disclosed in my pending application Serial No. 462,238.

The accompanying drawings illustrate my invention.

15 Figure 1 is a side elevation, with the package magazine in section; Fig. 2 a sectional detail of the coin supply holder and the adjacent delivery mechanism; Fig. 3 a sectional detail of a portion of the package 20 advancing mechanism; Fig. 4 a sectional detail of the means for retaining the coin supply in the holder to permit ready removal of the holder from the machine; Fig. 5 a sectional plan on line 5 5 of Fig. 1; Fig. 6 a 25 sectional plan immediately beneath the main table; Fig. 7 a section on line 7 7 of Fig. 6; Fig. 8 a sectional detail on line 8 8 of Fig. 6; Fig. 9 an elevation of the packaging magazine and adjacent parts on the side 30 opposite to that shown in Fig. 1; Fig. 10 a section on line 10 10 of Fig. 9; Fig. 11 a sectional detail of a crimper head; Fig. 12 a perspective detail of the crimping element 35 of the crimper head; Fig. 13 a sectional detail on line 15 15 of Fig. 9; Fig. 14 a similar view showing the receiving end of the container properly crimped to retain the coins; Fig. 15 a sectional detail on line 15 15 of Fig. 9; Fig. 16 a full size sectional detail of a modified and preferred form of crimper mechanism and its driving member of such character that it may be readily withdrawn from the 40 machine; Fig. 17 a plan of the structure shown in Fig. 16; Fig. 18 a fragmentary front elevation showing the manner of mounting the removable packaging magazine; Fig. 19 a fragmentary elevation of the 45 packager; Fig. 20 an axial section of one of the coin-holders and associated parts, and Fig. 21 a fragmentary vertical section of the delivery chute between the container magazine and the packaging head.

55 In the drawings 20 indicates a suitable supporting table having formed therein a

pair of perforations 21 and 22, the perforation 21 being of such size as to permit the axial passage of previously formed coin containers 23 and the perforation 22 being 60 of such size as to permit the passage of coins to be delivered to such coin containers. Arranged above table 20 in alinement with the perforation 21 is a delivery chute 23' through which the previously formed coin 65 containers 23 may be intermittently axially delivered by means of a controlling star wheel 24 automatically operated by mechanism which will be described later. Arranged upon table 20 above perforation 22 70 is a coin guide 25 having vertical guide faces 26 separated horizontally by a distance substantially equal to the diameter of the coin to be delivered to the perforation 22 and having a vertical height very slightly exceeding the thickness of such coin. This 75 guide plate is provided with a longitudinal slot 27 which extends through the major portion of its length so that any coin which may become stuck in the guide may be readily engaged by an instrument which will pass through said slot. At its delivery end the plate 25 is provided with a gradually curved downturned finger 28 against which a coin will be projected and compelled to 80 enter the perforation 22. Plate 25 is yieldingly held down by springs 25' so as to accommodate slightly thickened coins. Arranged in alinement with the receiving end of the guide 25 is a carrier 31 having guideways 85 90 95 100 105 110 ways 32 in alinement with the guideways 26. The carrier 31 is also provided with a vertical tubular sten 33 adapted to receive a coin holding tube 34 of any desired length said tube ending, at its lower end, immediately above the guides 32 a distance from the upper surface of the platform 20 just a trifle greater than the thickness of the coin to be carried within the tube. Arranged upon table 20 in horizontal alinement with the coin track formed by the guides 32 and 26 is an ejecting plunger 35 adapted to be reciprocated horizontally so as to engage the bottom coin of a stack within tube 34 and project said coin horizontally between guides 32 and 26 into engagement with the finger 28 and thence into perforation 22 through which it will fall. It sometimes occurs that coins will stack in the coin tube and it is therefore desirable to be able to readily remove the same from the machine and when that is done it is extremely desirable that

all of the coins within the tube be retained therein until the tube is replaced. This is also necessary if the counting operation is more rapid than the sorting. I therefore provide the carrier 31 with a beveled edge 36 adapted to be overlapped by the bevel edge 37 of a cam 38 pivoted upon table 20 and provided with a suitable operating arm or lever 39. The tube 34 is provided at its lower end with a pair of parallel longitudinal slits 41 which thus form a spring tongue 42. Pivoted upon the stem 33 is a lever 43 provided with a cam notch 44 adapted to engage a pin 45 projected through stem 33 and engaging the lower end of the spring tongue 42, the arrangement being such that, by turning lever 43 to the left (Fig. 1) this spring tongue 42 may be crowded against the coins within the tube 34 so as to hold the same therein and thus permit the withdrawal of the holder 31, with all its attached and contained parts.

Carried by a shaft 51 is a star wheel 52 (dotted lines Fig. 5) the arms of which project into the passageway formed between the flanges 26 of the guide 25. Shaft 51 carries a pinion 33 which meshes with a gear 54 carried by the units element of a counter 55 which, in the present instance is shown as an ordinary "Veeder" counter. Shaft 51 carries a pinion 56 at its lower end. The arms of the star wheel and the elements of the counter being so proportioned that passage of coins past the star wheel will actuate the counter in such manner as to produce a money reading of the counter equal to the money value of the coins forced past the star wheel.

Dependent from table 20 are brackets 61, two being provided for each of the packaging mechanisms (it being understood that there are as many packaging mechanisms embodied in one machine as may be desired either all of the same denomination or preferably one for each denomination of coin to be handled) and detachably secured to a pair of brackets between the same is a plate or carrier 62 in which is centrally journaled a shaft 63 carrying a plate 64 at its upper end. Plate 64 is perforated at a number of points (four in the present instance) in which are mounted the open-ended tubes 65 which are attached to receive previously formed coin containers 23 having a length slightly less than the distance from the upper surface of plate 62 to the upper surface of plate 64. Plate 64 is provided with a plurality of horizontally extending fingers 64', as many as there are tubes 65 and these fingers are uniformly spaced around the center or axis of the plate. The upper face of plate 64 comes into immediate engagement with the lower face of the block 67 carried upon the under face of table 20 and this block 67 is slightly shouldered at its upper

end 68 in order to receive and form a bearing for a gear 69 which is journaled freely upon the block 67 and is driven by pinion 56. Gear 69 carries a spring finger 71 which normally lies close upon the lower face of gear 69 but is adapted to be projected into engagement with any one of a series of pins 72 carried by plate 64, there being as many pins 72 as there are tubes 65. The spring finger 71 is provided, near its free end, with a stud 73 which projects up into a circular groove 74 formed in the upper face of gear 69 and projected down into this groove 74 is a pin 75 which will serve to intermittently engage pin 73 so as to project the free end of spring finger 71 into the position shown in Fig. 3. It is convenient to provide pin 75 with a threaded shank 76 and an operating head 77 so that the said pin may be readily moved into and out of operative position, for a purpose which will appear. The plate 64 at its center is provided with a socket 78 into which is projected the lower end of a pin 79 which may be readily withdrawn in order to permit the withdrawal of the packaging head, two of pins 72 and 172 being also withdrawn for that purpose.

Formed through plate 62, a quarter turn in advance of perforation 22 is a rectangular perforation 81 and below this perforation 95 is secured a guide 82 carrying a rectangular plunger 83 the upper end of which is notched at 84 and normally lies immediately below the upper surface of plate 62. Plunger 83 is connected at its lower end to a link 100 which is connected to a crank pin 86 carried by a mutilated gear 87 mounted upon a horizontal stud 88 which is carried by the plate 62. The gear 87 is provided, throughout the major portion of its circumference, with teeth adapted to mesh with the teeth of a gear 89 carried by a constantly rotating shaft 90 but these teeth are omitted at 91 so as to permit a free rotation of the pinion 89. Shaft 90 carries a single radially projecting finger 92 which is adapted to engage a finger 93 carried by gear 87 whenever said finger 93 is moved into proper position for such engagement and in order to cause such a movement, gear 87 carries a pin 94 adapted to engage a spiral pinion 95 splined upon the lower end of shaft 63. The said pinion having a limited axial movement upon shaft 63 and being normally urged to its lowest position by means of a spring 96 the arrangement being such that, if pin 94 be brought into engagement with the lower end of the spiral pinion at a time when said pinion was not in exactly proper position to permit the entry of said pin between two of its teeth, the pinion would yield upwardly but, so soon as the pinion was rotated and a proper engagement had between two of its teeth and the pin 94, a proper relative movement of pinion and pin would be had.

Immediately above the perforation 84, the table 20 is perforated at 101 for the reception of a crimper head which may be of the form shown in Fig. 11 or that shown in Fig. 16 or of any other desirable form. The especial details of construction of this crimper head are not material except that it should be of such character as to be capable of engaging the upper end of a coin container and crimping the same inwardly as shown in Fig. 14 or any other suitable manner, to retain the coins within the container. For this purpose it is desirable that the crimper head be provided with a crimping element 102 adapted to engage and crimp the edge or open end of the container. In the form shown in Figs. 1, 5 and 11, the crimper head is provided with a bevel gear 103 by means of which it may be rotated and this bevel gear meshes with a bevel gear 104 carried by a constantly rotating shaft 105. Such a construction is open to the objection that it is impossible to withdraw one of the crimper heads of a machine without stopping the entire machine and removing the shaft 105 and for that reason I prefer the form of crimper head shown in Figs. 16 and 17. This crimper head comprises a main shaft 106 carrying the crimper element 102, said crimper element being flanked on the outside by the outwardly flaring ring 107 and on the inside by the plug 108 which is formed integrally with shaft 106. The shaft 106 carries a key 109 which is splined in the keyway 110 of a spiral gear 111 which is journaled in the perforation 101 of table 20, said table being recessed at 101' at the upper end of perforation 101 to receive the tooth portion of the gear 111. The upper face of gear 111 is adapted to receive a thrust bearing 112 which is engaged at its upper side by a plate 113 carried by a casing member 114. The crimper shaft 106 is normally urged downwardly to its lowest position by means of a spring 115 which lies between ring 107 and gear 111 and thus rotates with said elements. Journaled in a suitable bracket 116 secured to the outer edge of table 20 is a shaft 117 carrying a spiral gear 118, adapted to mesh with the spiral gear 111, the bracket 116 having a portion 116' which forms a half casing for the gear 118 and meets with a portion 114' of the casing 114 to completely inclose the gear 118. The casing 114 is removably secured in position by means of screws 119 which enter the upper face of table 20, the arrangement being such that, by removing the screws 119, the crimper head may be quickly withdrawn, the gear 111 being easily withdrawable from the gear 118.

In order to rotate the packaging head I provide a finger 121 arranged in a horizontal plane of plate 64 and adapted to engage in one of the fingers 64' whenever the said

fingers are turned into the path of movement of the fingers. The finger 121 may be reciprocated by any suitable means but the reciprocation should be fairly rapid and therefore I find it convenient to mount said finger upon a head 122 which is connected with the coin ejecting plunger 35. The plunger 121 is mounted upon a vertical axis 123 and yieldingly urged in one direction by a spring 124 against a stop 125.

For the purpose of intermittently advancing the container feeder 24, the shaft of said feeder carries a bevel gear 126 which meshes with a bevel gear 127 carried by a shaft 128 which, at its lower end carries a star wheel 129, the arms of which are projected into the path of movement of any one of a series of four pins 72 carried by plate 64 the arrangement being such that there will be a forward step of the feeder wheel 24 upon each forward step of the packager head.

In order to properly position the packager head in its step by step advancement I provide in block 67 a spring plunger 132 which fits lightly within the upper end of one of the tubes 65 after the completed package has dropped therefrom, said completed package passing downwardly through a suitable perforation 130 formed through plate 62 at a point diametrically opposite the perforation 22 in table 20. It will be understood that the edge of the lower end of the plunger operates in the manner of an ordinary cupboard catch.

The operation is as follows: A supply of containers 23 is placed in the chute 23' delivering to the head 24 and these containers are intermittently fed downward so as to be delivered in a well known manner endwise through perforation 21 and into one of the tubes 65 of the packager head and this packager head is then advanced one-fourth of a turn by hand so as to bring the container 23 beneath perforation 22 whereupon one of the pins 72 comes into engagement with star wheel 129 and causes another advancing step of the head 24 so as to feed another container 23 down through perforation 21 to the next succeeding tube 65 of the packager head. The apparatus is now in condition for continued operation, it being assumed that the tube 34 is filled with a vertical stack of coins. A reciprocation of plunger 35 extracts the bottom coin from the coin stack and propels the same through the passage-way formed by the guides 32 and 26 and the reciprocation of the plunger 35 is long enough to propel the coin clear to the perforation 22, the forward part of the coin engaging the finger 28 and thus given a slight inclination downward as it falls through said perforation 22 and into the container 23. As the coin passes the star wheel 52 the counter 55 will be correspondingly actuated and the rotation of the star 130

wheel will cause a rotation of pinion 56 and a consequent forward movement of gear 69. This movement will continue until the arrival of the next to the last coin to be deposited into 5 the container and this next to the last coin will cause such an advancement of the gear 69 as will bring pin 73 into engagement with pin 75 and thus project the spring finger 71 down in the position shown in Fig. 3 10 immediately behind one of the pins 72 of plate 64. When the last coin passes the star wheel 52 gear 69 will be driven another step forward and the spring finger 71 will engage pin 72 so as to advance plate 64 very 15 slightly. Before this time finger 121 has been reciprocated from the position shown in Fig. 6 to the position shown in dotted lines in said figure but has not engaged plate 64 but as soon as the slight advancement 20 of plate 64 is produced by the last coin one of the fingers 64' of plate 64 is projected into the path of movement of finger 121 so that the said finger, as it moves forward at the time plunger 35 is moving 25 forward to project the first coin of the next series, will engage plate 64 and move the same suddenly through a quarter turn thus bringing a new coin container into alignment below perforation 22 to receive the first 30 coin of the new series. This forward movement of plate 64 and the packager head of which it forms a part causes a quarter turn of shaft 63 and therefore causes a quarter turn of the spiral pinion 95 which, acting upon 35 pin 94 of gear 87, causes a slight advancement of that gear so as to bring finger 93 into the path of movement of finger 92 so that the gear 87 is further slightly advanced so as to bring its teeth into engagement 40 with the teeth of pinion 89 and thereby permit a complete rotation or nearly complete rotation of gear 87 thus projecting the plunger 83 upwardly into engagement with the full container which, by the forward advancement of the packager head has 45 been brought above the plunger, so as to drive the full container upwardly through its tube 65 and bring its open end into engagement with the crimping element 102 of 50 the crimpler head. This crimpler head is continuously rotating so that, as the package is driven upwardly into engagement with the crimpler head the open end of the container is crimped inwardly and downwardly as 55 shown in Fig. 14 so as to rotate the coins within the container. So soon as the crimpler has produced the crimp the filled container moves downwardly by its own weight so as to again rest upon plate 62. The operation 60 from this point is repeated, and as the packager head is again advanced the filled and crimped container will be driven around to the perforation through plate 62 which will permit the escape of the completed coin 65 filled container.

It is important that the coin packaging mechanism and the mechanism for delivering the coins to the packages should be so intimately associated that a failure of operation of one will be concurrent with the failure of operation of the other so that the container which is being filled with coins cannot possibly be moved until the last coin of the predetermined number has been delivered to it and also such that whenever the final coin has been delivered to a package the previously filled package will be inevitably withdrawn from filling position and a new container brought to receiving position. For this purpose the carriage 122 which carries the plungers 121, is provided with upward projections 131 which project up through and fit within slideways 132 (Fig. 5) and to the upper end of each of these projections I secure one of the coin ejecting plungers 35 preferably by readily removable thumb screws 133 (Fig. 18). Carriage 122 is then connected by a pitman 134 with a crank 135 carried by a shaft 136 driven in any suitable manner as for instance by means of gears 137 and 138, the gear 138 being carried by the shaft of the main drive wheel 139 connected by a belt 141 with a small motor 142. By this arrangement plunger 121 cannot possibly engage the plate 64 of the packager head until it has been shifted by the last coin of any series and, just as soon as this slight movement takes place the plate 64 is in such position that if the coin ejecting 100 plunger ever can move forward through its ejecting movement the packager head will be advanced one step so as to bring a new coin container into receiving position to receive the first coin of the next series. 105

There are times when it may be desired to deliver a certain number of coins in bulk to a drawer or other container and for this purpose I arrange, immediately beneath the perforation 22 and beneath the packager head, a slide 151 which normally closes an opening 152 (Fig. 10) which leads to a chute 153 through which the coins may pass continuously to any suitable receptacle. For this use it is necessary that there be no rotation of the packager head and therefore pin 75 will be withdrawn from the path of movement of pin 73 so that there may be a continuous rotation of gear 69. 115

The counter 55 may be returned to zero 120 and the gear 69 to initial position by a reverse rotation of shaft 51, gear 69 coming to a stop whenever notice 155 of the gear 69 comes opposite a spring plunger 154.

I claim as my invention:

1. In a coin handling machine, the combination of a supporting table, a coin holder formed to hold a plurality of coins in a vertical stack on said table, a plunger, means for reciprocating said plunger transversely 130

of the holder to successively eject the bottom coin from the stack transversely from the holder and a member movable into and out of position to retain all the coins including 5 the lowermost coin within the holder.

2. In a coin handling machine, the combination of a supporting table, a coin holder formed to hold a plurality of coins in a vertical stack on said table, a plunger, means 10 for reciprocating said plunger transversely of the holder to successively eject the bottom coin from the stack transversely from the holder, a locking member for detachably holding the holder in position upon the 15 table and a member independent of the plunger and movable into and out of position to retain all the coins including the lowermost coin within the holder.

3. In a coin handling machine, the combination of a supporting table, a coin holder associated therewith and formed to hold a plurality of coins in position to be successively ejected, ejecting means associated with the holder, locking means for detachably 25 securing the holder in operative position with relation to the ejecting means, and a retainer carried by the holder and removable therewith, said retainer being movable in a position to retain all the coins including 30 the lowermost coin within the holder,

4. In a coin handling machine, the combination of a supporting table, a coin holder associated therewith and formed to hold a plurality of coins in position to be successively ejected, ejecting means associated with the holder, and means independent of the ejecting means and movable into and out of position to retain all the coins including the 35 lowermost coin in the holder.

5. In a coin handling machine, the combination of a supporting table, a coin holding tube arranged to hold a series of coins in a vertical stack, said tube being slitted at its lower ends to form a spring tongue, a member arranged to engage said tongue and move the same toward the axis of the tube to engage the lowermost coins therein and hold the stack of coins from outflow.

6. In a coin handling machine, the combination of a supporting table, a coin holding tube arranged to hold a series of coins in a vertical stack, said tube being slitted at its lower ends to form a spring tongue, a member arranged to engage said tongue and move the same toward the axis of the tube to engage the lowermost coins therein and hold the stack of coins from outflow, a carrier for said tube and a co-operating receiving portion on the table, and a movable 55 member for detachably holding said carrier in position upon the table.

7. In a coin handling machine, the combination of a coin holder formed to hold a plurality of coins in a vertical stack, a supporting table having a hole therethrough

for the passage of coins, a coin ejecting plunger, means for reciprocating said plunger transversely across the bottom of said holder to said hole, a coin guide associated with the table and leading from the holder to the hole and overlying the projected coin, and a downwardly inclined finger arranged at the end of said guide above the path of travel of the coin at the farther side of said hole.

8. In a coin handling machine, a substantially horizontal table having a vertical hole therethrough of a size slightly greater than a coin, a coin guide leading to said hole and overlying the same, and a downwardly extending finger arranged at the farther side of said hole and directed thereto.

9. In a coin handling machine, the combination of a coin holder formed to hold a plurality of coins in a vertical stack, a coin ejecting plunger, means for reciprocating said plunger transversely across the bottom of said holder, a guide plate having a coin groove in its lower face and mounted upon said table in the line of the ejecting plunger beyond the coin holder, means for yieldingly holding the plate down upon said table and a downwardly inclined finger 85 arranged at the end of said guide plate and directed toward an opening formed through the table, whereby each coin is inclined as it falls through said opening.

10. In a coin handling machine, a plurality of magazines for holding a plurality of previously formed coin containers, for coins of different denominations, a plurality of separate members for receiving and successively holding such containers in position to receive coins, a plurality of mechanisms for automatically delivering containers successively to the last mentioned holders, means for successively delivering predetermined numbers of coins into each container, and means for closing the containers to retain the coins therein.

11. In a coin handling machine, a plurality of magazines for holding a plurality of previously formed coin containers, for coins of different denominations, a plurality of separate members for receiving and holding such containers in position to receive coins, a plurality of mechanisms for automatically delivering containers successively to the last mentioned holders and mechanisms for closing the containers to retain the coins therein.

12. In a coin handling machine, a magazine for holding a plurality of previously formed coin containers, a separate member for successively receiving and holding such containers in position to receive coins, mechanism for automatically delivering containers successively to the last mentioned holder.

13. In a coin handling machine, a magazine for holding a plurality of previously

formed coin containers, a separate member for receiving and holding such containers in position to receive coins, mechanism for automatically delivering containers successively to the last mentioned holder and mechanism for closing the containers to retain coins therein.

14. In a coin packaging machine, the combination of a coin ejector arranged to eject successive coins from the coin holder, a packaging head formed to receive previously formed coin containers, an actuator for said head to move the same to intermittently withdraw a filled coin container from the coin-receiving position and bring a new coin container to coin-receiving position, a coin actuated member arranged in the path of movement of the ejected coin during its engagement by the coin ejector, and intermediate connections between said coin actuated member, and the packaging head for intermittently bringing the packaging head and its actuator into coöperative position to produce a movement of the packaging head.

15. In a coin packaging machine, the combination of a coin ejector arranged to eject successive coins from the coin holder, a packaging head formed to receive previously formed coin containers, an actuator for said head to move the same to intermittently withdraw a filled coin container from the coin-receiving position and bring a new coin container to coin-receiving position, intermediate connections between the coin ejector and the said actuator whereby the movement of said two parts will be synchronized, a coin actuated member arranged in the path of movement of the ejected coin during its engagement by the coin ejector, and intermediate connections between said coin actuated member and the packaging head for intermittently bringing the packaging head and its actuator into coöperative position to produce a movement of the packaging head.

16. In a coin packaging machine, the combination of a coin holder formed to hold a plurality of coins in an axial stack, a coin ejector arranged to eject successive coins from the coin holder, a packaging head formed to receive previously formed coin containers, an actuator for said head to move the same to intermittently withdraw a filled coin container from the coin-receiving position and bring a new coin container to coin-receiving position, a coin actuated member arranged in the path of movement of the ejected coin during its engagement by the coin ejector, and intermediate connections between said coin actuated member and the packaging head for intermittently bringing the packaging head and its actuator into coöperative position to produce a movement of the packaging head.

17. In a coin packaging machine, the combination of a coin holder formed to hold a

plurality of coins in an axial stack, a coin ejector arranged to eject successive coins from the coin holder, a packaging head formed to receive previously formed coin containers, an actuator for said head to move the same to intermittently withdraw a filled coin container to coin-receiving position, intermediate connections between the coin ejector and the said actuator whereby the movement of said two parts will be synchronized, a coin actuated member arranged in the path of movement of the ejected coin during its engagement by the coin ejector, and intermediate connections between said coin actuated member and the packaging head for intermittently bringing the packaging head and its actuator into coöperative position to produce a movement of the packaging head.

18. In a coin packaging machine, the combination of a coin ejector arranged to eject successive coins from the coin holder, a packaging head formed to receive previously formed coin containers, an actuator for said head to move the same to intermittently withdraw a filled coin container from the coin-receiving position and bring a new coin container to coin-receiving position, a coin actuated member arranged in the path of movement of the ejected coin during its engagement by the coin ejector, intermediate connections between said coin actuated member and the packaging head for intermittently bringing the packaging head and its actuator into coöperative position to produce a movement of the packaging head and closing mechanism arranged to close the open end of a filled container.

19. In a coin packaging machine, the combination of a coin ejector arranged to eject successive coins from the coin holder, a packaging head formed to receive previously formed coin containers, an actuator for said head to move the same to intermittently withdraw a filled coin container from the coin-receiving position and bring a new coin container to coin-receiving position, intermediate connections between the coin ejector and the said actuator whereby the movement of said two parts will be synchronized, a coin actuated member arranged in the path of movement of the ejected coin during its engagement by the coin ejector, intermediate connections between said coin actuated member and the packaging head for intermittently bringing the packaging head and its actuator into coöperative position to produce a movement of the packaging head, and closing mechanism arranged to close the open end of a filled container.

20. In a coin packaging machine, the combination of a coin holder formed to hold a plurality of coins in an axial stack, a coin ejector arranged to eject successive coins from the coin holder, a packaging head

- formed to receive previously formed coin containers, an actuator for said head to move the same to intermittently withdraw a filled coin container from the coin-receiving position and bring a new coin container to coin-receiving position, a coin actuated member arranged in the path of movement of the ejected coin during its engagement by the coin ejector, intermediate connections between said coin actuated member and the packaging head for intermittently bringing the packaging head and its actuator into co-operative position to produce a movement of the packaging head, and closing mechanism arranged to close the open end of a filled container. 21. In a coin packing machine, the combination of a coin holder formed to hold a plurality of coins in an axial stack, a coin ejector arranged to eject successive coins from the coin holder, a packaging head formed to receive previously formed coin containers, an actuator for said head to move the same to intermittently withdraw a filled coin container to coin-receiving position, intermediate connections between the coin ejector and the said actuator whereby the movement of said two parts will be synchronized, a coin actuated member arranged in the path of movement of the ejected coin during its engagement by the coin ejector, intermediate connections between said coin actuated member and the packaging head for intermittently bringing the packaging head and its actuator into co-operative position to produce a movement of the packaging head, and closing mechanism arranged to close the open end of a filled container. 22. In a coin handling machine, a packaging head comprising a plurality of receptacles for previously formed containers, an operating member arranged in conjunction with said head, intermediate separable connections between said operating member and the packaging head, means for intermittently bringing said separable connections into co-operative relation, coin delivering mechanism delivering to said packaging head, a coin actuated member arranged in the path of movement of the delivered coins, connections between said coin actuated member and the operating member of the packaging head and an actuator for said packaging formed to engage the packaging head and drive the same through the forward step subsequent to a movement of the package holding means by its operating member. 23. In a coin handling machine, the combination of a rotary packaging head comprising a plurality of receptacles for previously formed coin containers, a rotatable gear co-axial with said packaging head and independently movable, coin delivering mechanism arranged to deliver coins to said packaging head, a coin actuated member arranged in the path of movement of the delivered coins while under control of the delivering mechanism, intermediate connections between said coin actuated member and said gear, intermediate separable connections between said gear and said packaging head whereby a slight forward movement of the packaging head may be intermittently produced by the coin actuated member, means for controlling the interaction of said separable connections between the gear and packaging head, an actuator for the packaging head and members carried by the packaging head for engagement by the actuator subsequent to the preliminary movement of the packaging head produced by the coin actuated member. 24. In a coin handling machine, the combination of a rotary packaging head comprising a plurality of receptacles for previously formed coin containers, a rotatable gear co-axial with said packaging head and independently movable, coin delivering mechanism arranged to deliver coins to said packaging head, a coin actuated member arranged in the path of movement of the delivered coins while under control of the delivering mechanism, intermediate connections between said coin actuated member and said gear, intermediate separable connections between said gear and said packaging head whereby a slight forward movement of the packaging head may be intermittently produced by the coin actuated member, means for controlling the interaction of said separable connections between the gear and packaging head, an actuator for the packaging head, members carried by the packaging head for engagement by the actuator subsequent to the preliminary movement of the packaging head produced by the coin actuated member, and intermediate connections between said packaging head actuator and the coin delivering mechanism whereby the movements of said two parts are synchronized. 25. In a coin handling machine, the combination of a rotary packaging head comprising a plurality of receptacles for previously formed coin containers, a rotatable gear co-axial with said packaging head and independently movable, coin delivering mechanism arranged to deliver coins to said packaging head, a coin actuated member arranged in the path of movement of the delivered coins while under control of the delivering mechanism, intermediate connections between said coin actuated member and said gear, intermediate separable connections between said gear and said packaging head whereby a slight forward movement of the packaging head may be intermittently produced by the coin actuated member, means for controlling the interaction of said separable connections between the gear and packaging head, an actuator for the packaging head and members carried by the packaging head for engagement by the actuator subsequent to the preliminary movement of the packaging head produced by the coin actuated member, and intermediate connections between said packaging head actuator and the coin delivering mechanism whereby the movements of said two parts are synchronized.

tion of said separable connections between the gear and packaging head, an actuator for the packaging head, members carried by the packaging head for engagement by the actuator subsequent to the preliminary movement of the packaging head produced by the coin actuated member, a crimper head arranged to coöperate successively with filled containers carried by the packaging head, a plunger arranged to successively engage the filled containers and project the same into coöperative relation with the crimper, a carrier supporting said packaging head, gear, and plunger, an intermittent gear connected with the plunger for reciprocating the same, intermediate connections between the packaging head and said intermittent gear for slightly advancing said gear by the preliminary advancement of the packaging head, and a driving gear for said intermittent gear.

26. In a coin handling machine, the combination of a rotary packaging head comprising a plurality of receptacles for previously formed coin containers, a rotatable gear co-axial with said packaging head and independently movable, coin delivering mechanism arranged to deliver coins to said packaging head, a coin actuated member arranged in the path of movement of the delivered coins while under control of the delivering mechanism, intermediate connections between said coin actuated member and said gear, intermediate separable connections between said gear and said packaging head whereby a slight forward movement of the packaging head may be intermittently produced by the coin actuated member, means for controlling the interaction of said separable connections between the gear and packaging head, an actuator for the packaging head, members carried by the packaging head for engagement by the actuator subsequent to the preliminary movement of the packaging head produced by the coin actuated member, a crimper head arranged to coöperate successively with filled containers carried by the packaging head, a plunger arranged to successively engage the filled containers and project the same into coöperative relation with the crimper, a carrier supporting said packaging head, gear, and plunger, an intermittent gear connected with the plunger for reciprocating the same intermediate connections between the packaging head and said intermittent gear for slightly advancing said gear by the preliminary advancement of the packaging head, and a driving gear for said intermittent gear.

27. In a coin handling machine, the combination of a rotary packaging head comprising a plurality of receptacles for previously formed coin containers, a rotatable gear co-axial with said packaging head and independently movable, coin delivering mechanism arranged to deliver coins to said packaging head, a coin actuated member arranged in the path of movement of the delivered coins while under control of the delivering mechanism, intermediate connections between said coin actuated member and said gear, intermediate separable connections between said gear and said packaging head whereby a slight forward movement of the packaging head may be intermittently produced by the coin actuated member, means for controlling the interaction of said separable connections between the gear and packaging head, an actuator for the packaging head, members carried by the packaging head for engagement by the actuator subsequent to the preliminary movement of the packaging head produced by the coin actuated member, intermediate connections between said packaging head, actuator and the coin delivering mechanism whereby the movements of said two parts and synchronized, a crimper head arranged to coöperate successively with filled containers carried by the packaging head, a plunger arranged to successively engage the filled containers and project the same into coöperative relation with the crimper, a carrier supporting said packaging head, gear, and plunger, an intermittent gear connected with the plunger for reciprocating the same intermediate connections between the packaging head and said intermittent gear for slightly advancing said gear by the preliminary advancement of the packaging head, and a driving gear for said intermittent gear.

28. In a coin handling machine, the combination of a rotary packaging head comprising a plurality of receptacles for previously formed coin containers, a rotatable gear co-axial with said packaging head and independently movable, coin delivering mechanism arranged to deliver coins to said packaging head, a coin actuated member arranged in the path of movement of the delivered coins while under control of the delivering mechanism, intermediate connections between said coin actuated member and said gear, intermediate separable connections between said gear and said packaging head whereby a slight forward movement of the packaging head may be intermittently produced by the coin actuated member, means for controlling the interaction of said separable connections between the gear and packaging head, an actuator for the packaging head, members carried by the packaging head for engagement by the actuator subsequent to the preliminary movement of the packaging head produced by the coin actuated member, intermediate connections between said packaging head, actuator and the coin delivering mechanism whereby the movements of said two parts and synchronized, a crimper head arranged to coöperate successively with filled containers carried by the packaging head, a plunger arranged to successively engage the filled containers and project the same into coöperative relation with the crimper, a carrier supporting said packaging head, gear, and plunger, an intermittent gear connected with the plunger for reciprocating the same intermediate connections between the packaging head and said intermittent gear for slightly advancing said gear by the preliminary advancement of the packaging head, and a driving gear for said intermittent gear.

- quent to the preliminary movement of the packaging head produced by the coin actuated member, intermediate connections between said packaging head, actuator and the 5 coin delivering mechanism whereby the movements of said two parts are synchronized, a crimper head arranged to coöperate successively with filled containers carried by the packaging head, a plunger arranged to 10 successively engage the filled containers and project the same into coöperative relation with the crimper, a carrier supporting said packaging head, gear, and plunger, an intermittent gear connected with the plunger for 15 reciprocating the same, intermediate connections between the packaging head and said intermittent gear for slightly advancing said gear by the preliminary advancement of the packaging head, a driving gear for said intermittent gear, and means for detachably mounting the carrier in position to hold the parts carried thereby in coöperative relation with the coin delivering mechanism, the coin actuating member, the crimper head, and the 20 last mentioned gear.
29. In a coin handling machine, the combination with an intermittent rotatable packaging head, of a plunger arranged to successively engage coin containers carried by 25 said packaging head, a mutilated gear connected with said plunger for actuating the same, a spiral gear carried by the packaging head, a pin carried by the mutilated gear for intermittently engaging said spiral gear, and 30 a driving pinion for said mutilated gear.
30. In a coin handling machine, the combination with an intermittent rotatable packaging head, of a plunger arranged to successively engage coin containers carried by 35 said packaging head, a mutilated gear connected with said plunger for actuating the same, a spiral gear carried by the packaging head, a pin carried by the mutilated gear for intermittently engaging said spiral gear, a 40 spring for yieldingly holding the spiral gear in axial position and a driving pinion for said mutilated gear.
31. In a coin handling machine, the combination with a supporting table of a crimper 45 head comprising a rotatable crimping member, a spiral gear connected with said crimper member, a supporting table arranged to receive said crimper head and gear, a driving
- shaft journaled on said table, a spiral gear carried by said driving shaft and adapted to mesh with the spiral gear of the crimper head, a carrier for said crimper head and its spiral gear and means for detachably holding said holder upon the table with the two spiral gears in mesh, said holder being 55 withdrawable from the table substantially in line with the axis of the crimper head.
32. In a coin handling machine, the combination with a supporting table of a crimper head comprising a rotatable crimping member, a spiral gear connected with said crimper member, a supporting table arranged to receive said crimper head and gear, a driving shaft journaled on said table, a spiral gear carried by said driving shaft and adapted to 60 mesh with the spiral gear of the crimper head, a carrier for said crimper head and its spiral gear, said carrier incasing the crimper head gear and a portion of the coöperating gear, and means for detachably holding said holder upon the table with the two spiral gears in mesh, said holder being withdrawable from the table substantially in line with the axis of the crimper head.
33. In a coin handling machine, the combination of a coin actuated mechanism located in the path of travel of the coins, a magazine arranged to hold a plurality of previously formed containers, mechanism for delivering the containers in a vertical position to a holding means, said holding means arranged to present said containers to a position to be filled with coins, mechanism associated with the coin actuated mechanism for timing the delivery of the containers to the holding means and for timing the movement of the holding means toward the filling position, separate means for completing the delivery of the containers to the filling position, all of these movements being controlled by the coin actuated mechanism, and means for ejecting the coins past the coin actuated mechanism.
- In witness whereof, I have hereunto set my hand and seal at Indianapolis, Indiana, this thirtieth day of October, A. D. one thousand nine hundred and nine.
